PARTICULATE MATERIAL SPREADER

Loren E. Tyler, Wayzata, Minn., assignor to
Mobility, Inc., Long Lake, Minn.

Filed Sept. 2, 1969, Ser. No. 18,969

Term of patent 14 years

Int. Cl. D15—03

U.S. Cl. D35—2

FIG. 1

FIG. 2

FIG. 3

FIG. 7

FIG. 1 is a side elevational view of a particulate material spreader showing my new design;

FIG. 2 is a rear elevational view of the spreader of FIG. 1;

FIG. 3 is a front elevational view of the spreader of FIG. 1;

FIG. 4 is a plan view of the top of the spreader of FIG. 1 showing the covers in their closed position;

FIG. 5 is an enlarged sectional view taken along line 5-5 of FIG. 4;

FIG. 6 is a plan view similar to FIG. 4 showing the covers in their open positions; and

FIG. 7 is an enlarged sectional view taken along line 7-7 of FIG. 6.

I claim:

The ornamental design for a particulate material spreader, substantially as shown.
